UNITED STATES PATENT OFFICE.

RALEIGH B. BUZZAIRD, OF WASHINGTON, DISTRICT OF COLUMBIA, AND WORTHY CHANNING BUCKNAM, OF JERSEY CITY, NEW JERSEY, ASSIGNEES, BY MESNE ASSIGNMENTS, TO DAVIS AUTOMATIC EQUIPMENT CORPORATION, OF NEW YORK, N. Y., A CORPORATION OF NEW YORK.

COIN-CONTROLLED LOCK.

Application filed July 17, 1920. Serial No. 397,118.

To all whom it may concern:

Be it known that we, RALEIGH B. BUZZAIRD and WORTHY C. BUCKNAM, citizens of the United States, and residents, respectively, of Washington, in the District of Columbia, and of Jersey City, in the county of Hudson and State of New Jersey, have invented a new and useful Coin-Controlled Lock, of which the following is a specification.

10 The invention is an improvement in coin-controlled locks for use on public lockers. The object is to provide a simple, strong, compact and reliable mechanism for the purpose. To this end the invention may be said 15 to comprise the parts, improvements and combinations herein described and illustrated in preferred embodiment, and more particularly pointed out in the appended claims.

20 In the accompanying drawings, forming a part hereof:

Fig. 1 is a front or exterior elevation of the lock, in the unlocked condition, the key being caught in the lock;

25 Fig. 2 is a rear elevation of the lock in the same condition, showing a coin in the pocket of the coin-disk in readiness to be carried to the detent, to displace the same;

30 Fig. 3 is a rear elevation, showing the locking condition, in which the bolt is projected and the key removable, the coin being shown as having just tripped the detent and being about to drop out of the coin-disk in the manner indicated in dotted lines, the 35 cover of the coin-disk casing being removed for clearness of illustration;

Fig. 4 is a vertical section taken on the line 4—4 of Fig. 3;

40 Fig. 5 is a section on the line 5—5 of Fig. 2;

Fig. 6 is an elevation of the bolt;

Figs. 7 and 8 are inside perspective views of the body and cover of the coin-disk casing, respectively; and

45 Fig. 9 is a perspective view of the coin-disk.

The lock mechanism is mounted on a narrow elongated front plate or escutcheon 1, having suitable partial enclosure flanges 1^a 50 at the back, the plate being mounted in a vertical position in the frame of the locker adjacent the outer edge of the door to be locked. On the outer side this plate pre-

sents a turn knob 2 near the bottom, the entrance 3 of a coin drop above the knob, the 55 outer end of a key-cylinder and casing 4, 5 above the coin-entrance, and a window 6 near the top, through which the row of digits of a counter 7 is visible.

On the inner side of the plate is a bolt 60 8, the forward portion 9 of which is adapted to be projected and retracted through a slot in one of the vertical side flanges 1^a. This bolt is supported and guided by an elongated downwardly extending limb 10, adjacent 65 said flange, having its lower end connected to the plate by a pivot 11, about which the working end of the bolt swings in a comparatively flat arc. The bolt is also formed with a rear portion 12, which is dropped below the forward locking portion 9. The notch thus formed in the top of the bolt accommodates the inwardly projecting end of the key-cylinder 4 and its cylinder casing 5.

As is customary in this class of locks the 75 tumbler construction in the parts 4, 5 is such that the key 13 can be withdrawn and inserted in the locking position of the bolt, but cannot be withdrawn in the unlocked condition, the key being consequently locked in 80 the lock when the locker is open. These matters being familiar to those skilled in the art special illustration is unnecessary; and it will be understood that any suitable or known form of key-operated mechanism of 85 this general kind may be employed.

A bit 14 on the key-cylinder works in a recess 15 in the rear portion 12 of the bolt, against the shoulder 16 thus formed. The key means is employed for unlocking, the 90 projection of the bolt being effected automatically by a spring 17, which also turns the key-cylinder from the normal or unlocked position (with the key locked in) to the locked position, in which the key can be 95 taken out.

The bolt and the key-cylinder are held or confined in the unlocked position by a detent 18 in the nature of a bell-crank, which overlies the face of the limb 10 and rear portion 100 12 of the bolt, and is pivoted on a pin 19 projecting from the plate 1 in front of the upper part of said limb and below the working portion 9 of the bolt. The generally horizontal upper arm 20 of this detent is 105 formed with a blocking shoulder 21, which

cooperates with a projection 23 on the rear portion of the bolt to hold the same against locking movement under the action of the spring 17; and the detent is provided with a spring 24 which urges the detent to engage automatically with the bolt when the latter is retracted. The arm 20 also has an upwardly extending finger 22 behind the holding shoulders, which operates the counter 7, 10 through a link 22^a pivoted to the finger and to the crank-arm 25 of the counter.

The downwardly extending arm or limb 26 of the detent terminates in a contact extremity 27, projecting within the periphery 15 of a coin-disk casing 28. A coin-drop chute 29 is fixed or formed on the inner side of the plate in the space at one side of the limbs 10 and 26 and below the rear portions 12 and 20 of the bolt and detent, the upper 20 portion of this chute being behind the coin entrance 3 in the plate, and its open lower end being adjacent and conforming to the upper portion of the casing 28 at one side of the top thereof, the contact extremity 27 of the detent being at the other side.

In the casing 28 is a rotary coin-disk 30, having an eccentric coin pocket 31 on its rear face, to carry the coin a flat upon the disk with the edge of the coin projecting. 30 As illustrated, approximately one-half of the face of the disk is depressed or set back relatively to the other half a distance somewhat greater than the thickness of the coin to be used, the shoulder thus formed being 35 incurved or recessed at one side of the center to constitute the back of the pocket. For convenience of manufacture, the elevated area 32 may be made of a separate piece united to the body of the disk. The other 40 portion 33 of the shoulder, which may be substantially straight, prevents the coin-mover being turned the wrong way when the coin is in it, by crowding the coin against a stop 34 on the rear portion of the body 35 of the coin-disk casing and against the rear lower corner of the coin-drop. The 45 low region 36 of the disk adjacent the portion 33 of the shoulder constitutes a clearance which causes the coin to tilt forward 50 from the pocket as soon as it has actuated the detent. The coin may then immediately drop from the disk; or if it is momentarily sustained against the casing it cannot be carried backward since if the attempt is 55 made it will be locked between the casing and the shoulder 33.

The incurved or recessed portion of the shoulder, which forms the back of the coin-pocket 31, is deeper than the arc of the edge of the coin which occupies it, so that a dirt-pocket 31^a is formed, owing to the bearing on the coin-edge being at two points only, at the ends of the arm. Bearing at these two points will be preserved irrespective of accumulation of dirt, whereas if the arcs of

the shoulder and coin corresponded presence of foreign matter between them would interfere with proper seating of the coin on the disk. It follows, of course, that the shoulder need not necessarily be curved. 70

The coin-disk has a stem 37 which passes outward through an opening 38 in the plate, and is united with the knob 2. The periphery of the disk has a free turning fit in the casing body 35, which is in the form of a 75 shallow cup fixed to the back of the plate by a central neck 39 held in the opening 38 and forming a bearing for the stem 37. On the disk-encircling flange of the cup is an 80 outturned marginal flange 40, which need not necessarily extend all the way around, and which is substantially flush with or somewhat lower than the face of the coin-pocket 31, forming a guide for the projecting edge of the coin. 85

The remainder of the coin-disk casing is formed by a cover-plate 41, having portions 42 of a cylindrical flange, two of which are formed with slots 43 to interlock with lugs 44 on the body. The body may also be provided with portions 45 of a cylindrical flange, on the edge of the outturned flange 40. In any event the periphery of the casing is open beneath the coin-drop, at the 90 region of the contact portion 27 of the detent, and toward the bottom, for the escape of the coin. The said contact extremity is laterally guided by and substantially fills the width of the space between the flange 40 and the elevated marginal portion 41^b of the 95 cover 41, so as to intercept the edge of the coin. A rib or projection 41^a is pressed in from the marginal part of the cover at the 100 region of the detent, so as to bring this portion of the side guide close to the movable contact element, while leaving a wider space 105 elsewhere.

The operation will be briefly described. The lock is normally unlocked and the key locked in the lock. The user deposits his 110 property in the locker, shuts the door, drops a coin in the coin-entrance and turns the knob 2. The coin when deposited may drop directly into the coin pocket 31, if the disk happens to be in the precise position. 115 Otherwise it is sustained temporarily, within the lower end of the chute, upon the curved periphery of the full part of the coin disk, or upon the shoulder 33 and stop 34, until the turning of the disk brings the 120 pocket into position to receive it. Further movement causes the coin to press back the detent 18, thereby releasing the bolt 8, which is shot by its spring, thereby in turn moving the key cylinder 4 to position permitting 125 the removal of the key.

The locker is now locked and the user goes away with the key, which is his check. When he wishes to take out his belongings, he inserts the key, and turns it in the direc- 130

tion to unlock. This retracts the bolt, which is automatically caught and held by the detent, which also holds the key-cylinder in this position preventing removal of the key until after another coin has been introduced and the knob operated. A spring 46 behind the key-cylinder is provided for partially ejecting the key when the lock is locked, thus guarding against danger of the user 10 thoughtlessly turning the key in the unlock-
ing direction and then losing his service.

While the preferred embodiment of the invention has been described in detail, it will be understood that numerous changes in 15 form, proportions and relative arrangements may be made without departing from essentials.

What we claim as new is:

1. A coin-controlled locker lock comprising the combination of a bolt, a spring for actuating the bolt, a detent pivoted intermediate its ends for holding the bolt in retracted position against the action of the spring, a knob-operated freely-turning disk 25 coin-mover for releasing said detent, and key-operated mechanism for retracting the bolt, said key operated mechanism being of a character to lock the key against withdrawal except when the bolt is projected.

2. A coin-controlled locker lock comprising the combination of a bolt, a spring for actuating the bolt, a bell-crank detent for holding the bolt in retracted position against the action of the spring, a knob-operated 35 freely-turning disk coin-mover for releasing said detent, and key-operated mechanism for retracting the bolt, the key mechanism being of a character to lock the key against withdrawal except when the bolt is projected.

3. A coin-controlled locker lock comprising the combination of a generally vertically disposed pivoted bolt, a spring for actuating the bolt, a detent for holding 45 the bolt in retracted position against the action of the spring, a knob-operated rotary coin-disk substantially vertically below the bolt and detent for releasing said detent, and key-operated means for retracting the bolt.

4. A coin-controlled locker lock comprising the combination of a generally vertically disposed pivoted bolt, a spring for actuating the bolt, a pivoted detent for holding the bolt in retracted position against the action of the spring, a knob-operated rotary coin-disk substantially vertically below the bolt and detent for releasing said detent, and key-operated means over the bolt and 55 detent for retracting the bolt.

5. A coin-controlled locker lock, comprising the combination of a swinging bolt having a downwardly extending limb pivotally supported at its lower portion, a spring 65 for actuating the bolt, a bell-crank detent

cooperative with the upper portion of the bolt to hold the same retracted, said detent having a pivotal support at its upper portion and a limb extending downward from its pivot, a rotary coin-disk adjacent the free 70 lower end of said limb of the detent for actuating the same to release the bolt, and key-operated means for retracting the bolt, including a key which is locked in the lock when the bolt is retracted. 75

6. A coin-controlled locker lock, comprising the combination of a bolt having a downwardly extending limb pivotally supported at its lower portion, a spring for actuating the bolt, a detent cooperative with the bolt to hold the same retracted, said detent having a pivotal support at its upper portion and a limb extending downward from its pivot, a coin-drop at one side of said limbs, a rotary 80 coin-disk below the coin-drop and the limb of the detent and cooperative therewith, and key-operated means for retracting the bolt, including a key which is locked in the lock when the bolt is retracted. 85

7. In a coin-controlled locker lock, the combination of a bolt, a spring for actuating the same to lock, a coin-drop below the bolt, a detent cooperative with the bolt to hold the same retracted, said detent having a limb extending downward at one side of the coin-drop, a rotary coin-disk below the coin-drop and the limb of the detent and cooperative therewith, and key-operated means for retracting the bolt, including a key which is locked in the lock when the bolt is retracted. 90 95 100

8. A coin-controlled locker lock, comprising a bolt, a spring for actuating the same to lock, a key-cylinder over the bolt for retracting it, a coin-drop below the bolt, a detent for the bolt having a limb extending downward at one side of the coin-drop, and a rotary knob-operated coin-disk below the coin-drop and the limb of the detent and cooperative therewith. 105

9. A coin-controlled locker lock, comprising a bolt having a front portion, a rear portion, and a downwardly extending limb pivotally supported toward the bottom, a spring for actuating the bolt to lock, a key cylinder over the bolt for retracting the same, a detent lying in a plane adjacent to that of the bolt, pivotally supported at its upper portion in front of the bolt and having a rear portion cooperative with the rear portion of the bolt and a downwardly extending limb, a coin-drop in the recess formed by the rear portions and limbs of the bolt and detent, and a knob-operated rotary coin-disk below the coin-drop and the limb of the detent and cooperative therewith. 110 115 120 125

10. A coin-controlled locker lock, comprising a bolt having a front portion, a rear portion, and a downwardly extending limb pivotally supported toward the bottom, a 130

spring for actuating the bolt to lock, a key cylinder over the bolt for retracting the same, a detent lying in a plane adjacent to that of the bolt, pivotally supported at its upper portion in front of the bolt and having a rear portion cooperative with the rear portion of the bolt and a downwardly extending limb, a coin-drop in the recess formed by the rear portions and limbs of the bolt and detent, a knob-operated rotary coin-disk below the coin-drop and the limb of the detent and cooperative therewith, a counter over the key cylinder, and a connection between said counter and the rear portion of the detent.

11. In a coin-controlled locker lock, the combination of a spring-actuated bolt, a key-cylinder for retracting the same, a bell-crank detent cooperative with the bolt, a knob-operated rotary coin-disk cooperative with one arm of said bell-crank, a counter, and a connection between said counter and the other arm of the bell-crank detent.

12. A coin-controlled locker lock, comprising a spring-actuated bolt having an elevated front portion, a rear portion lower than the front portion and a downwardly extending limb pivotally supported toward the bottom, a key-cylinder over the bolt for retracting the same, a detent cooperative with the bolt, said detent being pivoted at its upper portion in front of the limb of the bolt and having a downwardly extending limb terminating in a free end, and a knob-operated rotary coin-disk cooperative with the free end of the detent limb.

13. In coin-controlled mechanism, the combination with a coin-drop and a detent, of a knob-operated rotary coin-disk below said coin-drop and detent having an eccentric coin pocket in its face, and a casing for said disk peripherally open at its upper region to receive the coin and the detent and at its lower region to permit escape of the coin, and provided at its rear peripheral region with a coin-stop which prevents the coin being carried in the wrong direction.

14. In coin-controlled mechanism, the combination of a turning coin-mover comprising a disk having an eccentric coin-

pocket on its face, and a casing for the disk comprising a cup having a marginal flange and a cover having a marginal portion opposite said marginal flange, the space between said marginal flange and marginal portion forming a passage for the edge of the coin projecting beyond the disk, and a detent having its end projecting between and closely embraced by the sides of said marginal passage.

15. In coin-controlled mechanism, the combination of a coin-disk having an eccentric coin-pocket upon its face, a member to be actuated projecting into proximity to the periphery of the disk, and side guides between which the contact portion of said member works and forming a passageway for the projecting edge of the coin, and a removable stationary cover for the disk, the marginal portion of which constitutes one of said side guides and is formed with a narrow inwardly projecting bearing cooperating with the side of the member.

16. A coin-controlled locker lock comprising the combination of a bolt, a spring for actuating the bolt, a coin drop, a detent for holding the bolt in retracted position against the action of the spring, said detent extending partially around said coin drop, a knob-operated freely turning disk coin mover for releasing said detent, and key-operated mechanism for retracting the bolt, said key-operated mechanism being of a character to lock the key against withdrawal except when the bolt is projected.

17. A coin-controlled locker lock comprising the combination of a bolt, a spring for actuating the bolt, a detent for holding the bolt in retracted position against action of the spring, said detent having a limb in angular relation to the detent arm for actuation by a coin, a knob-operated freely turning disk coin mover for releasing said detent, and key-operated mechanism for retracting the bolt, said key-operated mechanism being of a character to lock the key against withdrawal except when the key is projected.
